Primary Examiner — Rhea Shields

(57) CLAIM

The ornamental design for a bath sponge shower brush, as shown and described.

DESCRIPTION

FIG. 1 is a perspective view of a bath sponge shower brush showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

In the drawings, the broken lines are for the purpose of illustrating portions of the bath sponge shower brush that forms no part of the claimed design.

1 Claim, 7 Drawing Sheets
